UNITED STATES PATENT OFFICE

FRANCIS H. TREAT, OF BELLEVUE, OHIO, ASSIGNOR TO DUFF PATENTS COMPANY, INC.,
OF PITTSBURGH, PENNSYLVANIA, A CORPORATION OF PENNSYLVANIA

GAS PRODUCER

Application filed November 12, 1926. Serial No. 147,945.

This invention relates to gas producers, and more particularly to producers of the mechanical type.

This invention relates primarily to producers of the mechanical type wherein the body part of the producer is stationary and wherein mechanical feeding and agitating means is provided at the top thereof, and wherein ash removing means is provided at 10 the bottom thereof.

According to the present invention it is proposed to provide an ash removing means for producers of this type wherein the ashes will be most effectively removed and discharged at a given point at one side of the producer and wherein an effective water-seal is provided for the ash receiving pan.

The invention may be readily understood by reference to the accompanying drawings, 20 in which—

Figure 1 represents a vertical section through a producer embodying the present invention;

Figure 2 is a plan view of a portion of the 25 ash pan, showing the scraper for removing ashes from the pan; and

Figure 3 is a detail view in vertical section, showing the water outlet passage through the cone-like member.

30 In the drawings, 2 designates the body of the gas producer. At the top of the producer is a fuel feeding top 3, which may be of any known or preferred construction, and which preferably is constructed in accordance with 35 the invention disclosed in my copending application, Serial No. 147,944, filed November 12, 1926.

Associated with the fuel feeding top is an agitator 4. In the lower part of the producer 40 in the fuel bed thereof are tuyères 5 which are preferably of the construction shown in my copending application, Serial No. 753,433, filed December 2, 1924. Depending from the lower end of the producer is an inwardly sloping apron 6.

Rotatably supported at the bottom of the producer on a base 7 is an ash pan 8 which has outwardly sloping sides 9. At the center of the ash pan is an inwardly sloped annular flange 10 having an inverted cone-like casting

11 thereon, this casting having radial ribs or fins 11^a on its surface. The casting 11 is held in spaced relation to the flange 10 by means of bosses 11^b at its lower edge. This permits of the flow of water between the cone and the 55 inwardly sloping flange 10, as hereinafter more fully described.

Mounted on the base 7 at suitable points are supporting rollers 12 which engage a bearing surface 13 on the under side of the 60 pan. The under side of the pan is also provided with an annular rack 14 for engagement with a driving pinion 15 on the horizontal shaft 16 supported on the base 7. The shaft 16 with its driving pinion 15 provides 65 means for effecting the rotation of the ash pan, it being contemplated that a motor or other suitable guiding means be connected to the shaft 16.

At the center of the ash pan is a vertical 70 shaft 17 which provides the central post about which the pan rotates, and which is hollow. Located inside the inwardly sloping flange 10 is a horizontal plate 18 which is secured thereto and which has a central 75 pipe 19 depending therefrom, the lower end of this pipe projecting into the hollow shaft 17.

The arrangement is such that a normal water level can be maintained in substantially 80 the plane of line A—A of Figure 1. Water will be supplied to the ash pit in any suitable way, and the overflow can take place by the water flowing between the upper part of the inwardly sloping flange 10 and the under 85 surface of the cone 11, the water falling over the upper edge 10^a of its flange on to the plate 18, from whence it can flow out the discharge pipe 19 and the central shaft 17. 90

Inasmuch as the apron 6 extends well down into the ash pan, the lower end of the producer is effectively sealed by the water in the pan. The arrangement of the overflow is of particular advantage in that it provides 95 an effective seal at the base of the cone 11 and yet permits of the central removal of the water. Since the water is removed from the center of the pan, there are no pipes to interfere with the operation of the scrapers, 100

as hereinafter described, and the overflow is not likely to become clogged with ashes.

Secured to the apron 6 on the stationary body of the producer is a plow member 20.

6 If desirable, a plurality of these plows may be provided. The plows are preferably formed of a piece of angle iron, and they project down into the ash pan close to the bottom thereof and well below the lowermost edge of the apron 6.

10 Carried on a fixed bracket 22, projecting laterally from the base of the producer near the top of the apron 6 or otherwise suitably supported, is a scraper 23. This scraper extends down into the ash pan close to the sloping sides 9 thereof and is inclined in a direction opposite the direction of rotation of the pan. This scraper, which is preferably formed of angle iron, has a beveled lower end 15 adapted to ride on the bottom of the pan. If necessary more than one scraper may be provided.

15 In the operation of the producer the ash pan may be continuously or intermittently rotated. The bed of fuel in the producer will be stationary, while the ashes immediately above the cone 11 are carried around with the rotation of the pan. The ashes tend to seek a natural angle of repose in the ash 20 pan, but since they are carried around with the rotation of the pan, the plows 20 tend to disturb them and force them outwardly so that other ashes descending from the producer will replace them. Thus, ashes which 25 have been forced to the outside of the pan are carried around with the rotation of the pan until their travel is obstructed by the inclined scraper 23. The ashes are forced to ride up this scraper and to be discharged over 30 the edge of the pan. The agitation produced by the revolving center cone 11 will overcome the tendency of the ashes to pack below the tuyères, and this loosening of the ashes is stimulated by the ashes which move around 35 with the pan, rubbing against and coming in contact with the stationary ashes above them in the producer. An effective means for securing the removal of the ashes is thus secured.

40 50 An important advantage of the invention resides from the provision of a rotatable ash pan at the base of a stationary producer, together with the provision of the plows and scrapers for effecting the loosening and removal of the ashes.

55 A further advantage resides from the provision of the central cone 11, while the arrangement is considerably simplified by the provision of the central overflow for the water 60 in the ash pit.

The construction, furthermore, is one which can be built at relatively low expense.

65 While I have described a preferred embodiment of my invention, it will be understood that various changes and modifications may

be made therein, and that the invention may be otherwise embodied and employed in connection with producers of a type other than the particular type illustrated.

I claim:

1. A gas producer comprising a body, an ash pan at the lower end of the body, means for rotating the ash pan, said ash pan having an outer outwardly sloped wall spaced away from the lower end of the body and extending up around the lower end of the body and having a concentric inwardly sloped wall of less height than the outer wall, an inverted cone-like member supported on the inner wall, water-circulating conduits being provided between said cone-like member and said inner wall to cause the water to flow under the cone, and water discharge means within said inner wall.

2. In a mechanical gas producer of the type having a stationary body adapted to receive the fuel bed and a rotatable ash pan with the lower end of the body projected into the pan, blast tuyères extending radially into the producer from the side walls thereof only part way to the center of the fuel bed and in a plane above the level of the ash pan, said tuyères being adapted to project into the fuel bed and restrain it against rotation with the ash pan and constituting the only source of air supply to the producer, and a central cone-like member supported by the ash pan, the top of the cone-like member terminating below the plane of the tuyères.

3. In a mechanical gas producer of the type having a stationary body adapted to receive the fuel bed and a rotatable ash pan with the lower end of the body projected into the pan, blast tuyères extending radially into the producer from the side walls thereof only part way to the center of the fuel bed and in a plane above the level of the ash pan, said tuyères being adapted to project into the fuel bed and restrain it against rotation with the ash pan and constituting the only source of air supply to the producer, a central cone-like member supported by the ash pan, the top of the cone-like member terminating below the plane of the tuyères, a plow member on the lower end of the body projecting into the ash pan for loosening the ashes around the base of the central cone and forcing them toward the outside of said pan, and a fixed scraper projecting into the pan along the outer edge thereof and inclined toward the direction of travel of the pan for removing ashes from the pan.

4. A gas producer comprising a relatively rotatable concentric body adapted to contain a solid fuel bed, an ash pan, said ash pan having a central inverted cone-shaped member extending up into the body for supporting most of the fuel and ashes within the body, and means for causing water within the ash pan to overflow directly under said

cone-shaped member at a predetermined level, and means other than said cone-shaped member for exclusively supplying the fuel bed in said body with air.

5 In testimony whereof I have hereunto set my hand.

FRANCIS H. TREAT.
